DESIGN FOR A GLASS BOTTLE

John H. Meier, Jr., Pittsburgh, Pa., assignor to J. T. & A. Hamilton Company, Pittsburgh, Pa.,
a corporation of Pennsylvania

Application March 19, 1942, Serial No. 106,256

Term of patent 3½ years

To all whom it may concern:

Be it known that I, John H. Meier, Jr., a citizen of the United States, residing at Pittsburgh, in the county of Allegheny and State of Pennsylvania, have invented a new, original, and ornamental Design for a Glass Bottle, of which the following is a specification, reference being had to the accompanying drawing, forming part thereof.

In the drawing—

Fig. I is a view in front elevation of a glass bottle showing my new design; Fig. II is a view of the bottle in plan from above; and Fig. III is a view of the bottle in plan from below.

The back of the bottle is identical with the front.

I claim:

The ornamental design for a glass bottle, substantially as shown and described.
